UNITED STATES PATENT OFFICE.

HENRY M. COLLESTER, OF GARDNER, MASSACHUSETTS.

DESIGN FOR CANE FABRIC.

SPECIFICATION forming part of Design No. 26,552, dated January 19, 1897.

Application filed December 11, 1896. Serial No. 615,409. Term of patent 7 years.

To all whom it may concern:

Be it known that I, HENRY M. COLLESTER, of Gardner, in the county of Worcester and State of Massachusetts, have invented and 5 produced a new and original Design for Cane Fabric, of which the following is a specification.

Reference is to be had to the accompanying drawing, forming a part of this specification, 10 which shows a piece of cane fabric with my design applied.

The leading feature of my design consists of the arrangement of companion parallel stripes *a a* between the companion parallel 15 stripes *b b*, each of said pairs of stripes being of a contrasting color from the body of the fabric and from each other, and each stripe being depressed upon its margin to show the 20 body of the fabric as alternating marginal 25 checks.

f represents a piece of cane fabric bearing my design, which consists of the arrangement of parallel companion stripes *a a* between parallel companion stripes *b b*. Each pair of these stripes is of a contrasting color from the body of the fabric and from each other, and each stripe is depressed upon its margin to show the body of the fabric as alternating marginal checks. 30

I claim—

The design for cane fabric, as herein shown and described.

In testimony whereof I have signed my name to this specification, in the presence of two subscribing witnesses, this 30th day of 35 November, A. D. 1896.

HENRY M. COLLESTER.
